US0D1085706S

(12) United States Design Patent (10) Patent No.: US D1,085,706 S
(45) Date of Patent: * Jul. 29, 2025

(54) BAG

(71) Applicant: ROTHY'S, INC., San Francisco, CA (US)

(72) Inventors: William Roth Martin, San Francisco, CA (US); La Vion Gibson, San Francisco, CA (US); Manon Julien, London (GB)

(73) Assignee: ROTHY'S, INC., San Francisco, CA (US)

() Term: 15 Years

(21) Appl. No.: 29/914,137

(22) Filed: Oct. 13, 2023

Related U.S. Application Data

(62) Division of application No. 29/726,146, filed on Feb. 28, 2020, now Pat. No. Des. 1,022,462.

(57) CLAIM

The ornamental design for a bag as shown and described.

DESCRIPTION

FIG. 1 is a perspective view of a bag showing our design, wherein the right side is a mirror image of the left side; FIG. 2 is front view of the design shown in FIG. 1; FIG. 3 is a rear view of the design shown in FIG. 1; FIG. 4 is a top view of the design shown in FIG. 1; FIG. 5 is a bottom view of the design shown in FIG. 1 with the sides of the bag in an alternative position; and, FIG. 6 is an enlarged view of a portion of FIG. 4. The dot-dash lines in FIGS. 4 and 6 depict the boundaries of an enlargement and form no part of the claimed design. FIG. 5 includes dash-dot lines surrounding grayed out portions of the article that form no part of the claimed design.

1 Claim, 6 Drawing Sheets
